ATTORNEY

UNITED STATES PATENT OFFICE.

ALFRED SPANEY, OF PIERMONT, NEW YORK.

BROOCH.

1,246,670.

Specification of Letters Patent.

Patented Nov. 13, 1917.

Application filed August 2, 1916. Serial No. 112,686.

To all whom it may concern:

Be it known that I, ALFRED SPANEY, a citizen of the United States, residing at Piermont, Rockland county, in the State of New York, have invented certain new and useful Improvements in Brooches, of which the following is a full, clear, and exact specification.

This invention relates to improvements in jewelry, and has for its object more particularly to provide a brooch comprising a plurality of parts or members one of which may be worn separately or in combination with one or more of the other parts. 10
One of the objects of the invention is to provide a brooch comprising a main or pin member and a supplemental member adapted to be fitted thereon in order to form a brooch therewith. 15
Another object of the invention is to provide a brooch comprising a plurality of members adapted to be assembled to present the appearance of a single brooch, and still permit of the removal or changing of some 20 of the members.

Another object of the invention is to provide a brooch set comprising a plurality of members of different designs any one of which is adapted to be fitted to another member to form a brooch whereby a plurality of brooches of different designs may be formed. 30

Another object of the invention is to provide a brooch having a recessed portion to receive any one of a series of separable members which may be of various colors or combination of colors so that the brooch may be made to harmonize with the gown of the wearer. 35

Other objects will in part be obvious and in part pointed out hereinafter.

To the attainment of the aforesaid objects and ends, my invention consists in the novel details of construction, and in the combination, connection and arrangement of parts hereinafter more fully described and then pointed out in the claims. 45

In the accompanying drawings showing illustrative embodiments of the invention—

Figure 1 is a front view of one form of brooch constructed according to and embodying my said invention;

Fig. 2 is a sectional view taken on the line 2—2 of Fig. 1;

Fig. 3 is a front view of the main or pin member separated from the supplemental member;

Fig. 4 is a side view thereof;

Fig. 5 is a front view of the supplemental member separated from the main or pin member;

Fig. 6 is a front view of a main or pin member of a different design than that shown in Fig. 3;

Fig. 7 is a front view of another form of brooch;

Fig. 8 is a sectional view taken on the line 8—8 of Fig. 7, and

Fig. 9 is a sectional view on the line 9—9, Fig. 7.

Referring to Figs. 1 to 5 inclusive of the drawings the brooch 10 is shown composed of a main or pin member 11 and a supplemental member 12 adapted to be detachably fitted thereon. It will, of course, be understood that the members 11 and 12 may be of any suitable shape, size or design, and that they may be jeweled or not as desired without in any way departing from the spirit of the invention which does not relate to the particular shape, size or design of the brooch or the parts thereof. 70

Secured to the back of the main member 11, which for purposes of illustration is shown in the form of a bar or breast pin, is 85 a hinged pin 14 and a catch 15 of usual construction for fastening the member to an article of clothing. At the rear of the member 11, and concealed from view from the front thereof, is a threaded socket 16 the purpose of which will be explained hereinafter. 90

The supplemental member 12, as shown, comprises two portions 17, 17 spaced from one another and united by connecting members 18, 18, and 19 the front surfaces of which lie in rear of the front surfaces of the spaced portions 17 to provide a seat for the main member 11 which, when the members of the brooch are assembled, is positioned between the spaced portions 17, 17 of the supplemental member 12 with the pin 14 in rear of the connecting members 18, 18, and 19. 95

Rotatably supported upon the connecting member 19 is a screw 20 having its threaded end extending forwardly whereby it is adapted to engage the threaded socket 16 in the main member 11 to hold the members 11 and 12 against relative movement when they are assembled to form a brooch. The screw 105 20 has a reduced shank portion 21 engaging a hole 22 in the connecting member 19, and a head 23 engaging the rear surface of the connecting member 19 whereby the screw 20 110

is held against longitudinal movement. A finger gripping member 24, for rotating the screw 20, is hinged to the head 23 thereof to permit of its being folded into substantial parallelism with the rear surface of the brooch whereby it will not interfere with the fastening of the brooch to an article of clothing by means of the pin 14 and catch 15.

Fig. 6 shows a main or pin member 25 differing in design from the one shown in Fig. 3, and adapted to be assembled with the supplemental member 12 in the manner above described to form a brooch, the design or appearance of which will differ from the design or appearance of the brooch formed by the assembling of the main member 11 with the supplemental member 12. Furthermore the jewels upon one of the main members may be of different color than those upon the other main member whereby the color scheme of the assembled brooches may be varied at will, or to harmonize with the color of the gown of the wearer.

It will thus be seen that a brooch set is provided consisting of a plurality of main members of different shape, size or design, and a supplemental member. In use any one of the main members may be worn by itself as a breast pin, or any one of them may be assembled with the supplemental member to form a brooch whereby it is possible to form a plurality of brooches differing from one another in appearance.

It will, of course, be understood that it is within the scope of the invention to provide a brooch set consisting of but one main member and a plurality of supplemental members of different shape, size or design, any one of which is adapted to be assembled with the main member whereby a plurality of brooches may be formed, or if desired a brooch set may be provided consisting of a plurality of main members and a plurality of supplemental members any one of which supplemental members may be assembled with any one of the main members to form a brooch.

Referring to Figs. 7, 8 and 9, there is shown a modified form of the invention. In these figures the brooch 26 comprises a main member 27 and two supplemental members 28 and 29 adapted to be fitted thereto. The main member 27 is similar in construction to the main members 11 and 25 and is adapted to be secured to the supplemental member 28 in the manner hereinbefore described. The supplemental member 28, which is similar in construction to the supplemental member 12, comprises two spaced portions united by connecting members 30, 30, and 30^a. The supplemental member 29, which in its assembled position is adapted to embrace the supplemental member 28, comprises two spaced portions united by connecting members 31 adapted to be positioned alongside

of and in register with the connecting members 30 of the supplemental member 28 whereby longitudinal movement of the supplemental member 29 is prevented. The supplemental member 29 is otherwise maintained in position when in use by the friction between the co-engaging surfaces of said supplemental member and the supplemental member 28 and by the portion of the clothing which lies between the pin and the rear surface of the brooch.

Having thus described my said invention, what I claim and desire to secure by Letters Patent is:—

1. A brooch of the character described, comprising an ornamental main member provided with fastening means for attachment to an article of clothing and constituting a complete article of jewelry, and an ornamental supplemental member removably fitted upon said main member and free from connection with said fastening means, substantially as specified.

2. A brooch of the character described comprising an ornamental main member provided with fastening means for attachment to an article of clothing and constituting a complete article of jewelry, and an ornamental supplemental member removably fitted upon said main member and free from connection with said fastening means, said members being provided with co-acting means to retain said supplemental member in position, substantially as specified.

3. A brooch of the character described comprising an ornamental main member provided with fastening means for attachment to an article of clothing and constituting a complete article of jewelry, and an ornamental supplemental member removably fitted upon said main member and free from connection with said fastening means, said members being provided with co-acting locking means to retain said supplemental member in position, substantially as specified.

4. A brooch of the character described comprising an ornamental main member provided with fastening means for attachment to an article of clothing and constituting a complete article of jewelry, and an ornamental supplemental member removably fitted upon and embracing said main member and free from connection with said fastening means, substantially as specified.

5. A brooch of the character described comprising an ornamental main member provided with fastening means for attachment to an article of clothing and constituting a complete article of jewelry, and an ornamental supplemental member removably fitted upon said main member and free from connection with said fastening means, said supplemental member being provided with a recess to receive said main member, substantially as specified.

6. A brooch of the character described comprising an ornamental main member constituting a complete article of jewelry and a supplemental member removably fitted thereon and comprising two ornamental portions held in spaced relation to one another, said main member being positioned between the spaced portions of said supplemental member and being provided with fastening means whereby the brooch may be secured to an article of clothing, substantially as specified.

7. A brooch of the character described comprising an ornamental main member constituting a complete article of jewelry and a supplemental member removably fitted thereon, said supplemental member comprising two ornamental portions and connecting members holding said portions in spaced relation to one another, said main member being positioned between the spaced portions of said supplemental member and in engagement with said connecting members, said main member being provided with fastening means whereby the brooch may be secured to an article of clothing, substantially as specified.

8. A brooch of the character described comprising an ornamental main member constituting a complete article of jewelry and a supplemental member removably fitted thereon, said supplemental member comprising two ornamental portions and connecting members holding said portions in spaced relation to one another, said main member being positioned between the spaced portions of said supplemental member in front of and in engagement with said connecting members, said main member being provided with fastening means in rear of said connecting members whereby the brooch may be secured to an article of clothing, substantially as specified.

9. A brooch of the character described comprising an ornamental main member constituting a complete article of jewelry and a supplemental member removably fitted thereon and comprising two ornamental portions held in spaced relation to one another, said main member being positioned between the spaced portions of said supplemental member and being provided with fastening means whereby the brooch may be secured to an article of clothing, said members being provided with co-acting locking means to hold them in assembled relation to one another, substantially as specified.

10. A brooch of the character described comprising a plurality of separable members, a screw rotatably supported upon one of said members and provided at its rear

end with a folding finger gripping portion for rotating the screw, the other of said members being provided with a threaded 65 socket to be engaged by said screw to hold said members in assembled position, one of said members being provided with fastening means whereby the brooch may be secured to an article of clothing, substantially as speci- 70 fied.

11. A brooch of the character described comprising an ornamental main member provided with fastening means for attachment to an article of clothing and constituting a 75 complete article of jewelry, and an ornamental supplemental member removably fitted upon said main member and having a portion positioned in rear thereof, said main member and said portion of said supplemental member being provided with co-acting 80 means to hold said members in assembled position, substantially as specified.

12. A brooch of the character described comprising an ornamental main member provided with fastening means for attachment to an article of clothing and constituting a complete article of jewelry, and an ornamental supplemental member removably fitted upon said main member and having a 85 portion positioned in rear thereof, said portion of said supplemental member carrying a locking member, said main member being provided with means to be engaged by said locking member to hold the brooch members 90 in assembled position, substantially as specified.

13. A brooch of the character described comprising an ornamental main member constituting a complete article of jewelry, and 100 a supplemental member removably fitted thereon, said supplemental member comprising two ornamental portions and a connecting member holding said portions in spaced relation to one another, a locking member 105 carried by said connecting member, said main member being positioned between the spaced portions of said supplemental member and being provided with means to be engaged by said locking member to hold the 110 brooch members in assembled position, said main member being provided with fastening means whereby the brooch may be fastened to an article of clothing, substantially as specified.

Signed at the city of New York, in the county and State of New York, this 12th day of June one thousand nine hundred and sixteen.

ALFRED SPANEY.
